US00D337157S

United States Patent

[19]

Ortiz[11] **Patent Number:** **Des. 337,157**[45] **Date of Patent:** **** Jul. 6, 1993****[54] REPLACEMENT VALVE FOR
ENDOTRACHEAL TUBE INFLATION CUFF**4,653,539 3/1987 Bell ..... 128/207.15 XR
4,856,510 8/1989 Kowalewski ..... 604/100[76] **Inventor:** **German L. Ortiz, 72685 Colerain,
Dillonvale, Ohio 43917****FOREIGN PATENT DOCUMENTS**971457 2/1975 Canada .
810517 1/1957 United Kingdom .[**] **Term:** **14 Years***Primary Examiner*—Stella Reid*Assistant Examiner*—I. Simmons*Attorney, Agent, or Firm*—Terry M. Gernstein[21] **Appl. No.:** **702,720****[57] CLAIM**[22] **Filed:** **May 20, 1991****The ornamental design for a replacement valve for
endotracheal tube inflation cuff, as shown and de-
scribed.**[52] **U.S. Cl.** **D24/129; D24/110**
[58] **Field of Search** **D24/129, 110;
128/202.22, 207.15, 207.16, 911, 912; 604/97,
99****[56] References Cited****DESCRIPTION****U.S. PATENT DOCUMENTS**
